1**2,727,244****NECKTIE FORMING AND SECURING DEVICE**

Kjartan Kristjansson, Brooklyn, N. Y.

Application June 22, 1953, Serial No. 363,055

1 Claim. (Cl. 2—153)

This invention relates to new and useful improvements in necktie forms, and means for securing a necktie solidly in the tied shape.

Thus, it is the purpose of this invention to provide a device, which in the above regard is infallible in operation, and very cheap to manufacture.

With the above and other objects in view, this invention consists of the novel features of construction, combination and arrangement of parts, hereinafter fully described, claimed and illustrated in the accompanying drawing, forming part of this application, and in which similar characters of reference indicate corresponding parts in all views, and in which:

Figure 1 is an elevational view, showing a tie wound upon and shaped according to my device.

Figure 2 is an elevational view of my said device.

Figure 3 is a sectional view, taken on the line 3—3 in Figure 2.

Figure 4 is a bottom view of my device; while

Figure 5 is a detail view of the tie securing member.

Referring more particularly to the drawing, Figure 1 shows a tie wound around or upon a form, or base 10 shown in Figure 2.

The said form 10 is provided with a slanting upper edge portion 11, and has its sides slightly inwardly bent, as at 12, with a downwardly tapered body portion 13, which terminates in a semi-tubular end portion 14.

A member 15, having the shape substantially of a 45 degrees circle, with one side 20 shorter than the other side 21 to allow room for a tie flap in the semi-tubular end portion, is pivotally secured at the bottom of the tie-form 10 in said end portion, by a pin or rivet 16, in such a manner that said member will normally, due to gravity, depend from the lower end of said semi-tubular end portion 14.

The said member 15 will, by being capable of being swung outwardly and substantially all clear of the open-

ing 17 in the semi-tubular end portion, as shown in dotted lines at 19, readily permit the insertion of an inner necktie flap 18 through said opening, when in the process of winding or tying the tie upon the tie-form 10, while by subsequently moving or turning said member 15 back and inward into the opening 17 after said tie flap has been inserted in the opening, said member 15 will solidly grip said tie flap, and thereby prevent the latter from getting loose, and thus prevent a dislocation of the necktie proper.

By the position the member 15 is susceptible of assuming, as shown at 19, the operation of the device becomes extremely easy.

It should in this connection be noted, that in order to obtain sufficient space for the insertion of the tie flap 18 through the semi-tubular end portion 14, the member 15 is pivotally secured at the extreme edges of said end portion, as shown in Figure 4.

It is obvious that changes may be made in the form, construction and arrangement of the several parts, within the scope of the appended claim, without departing from the spirit of the invention, and I do not, therefore, wish to limit myself to the exact construction shown and described herein.

25 What I claim as new, and desire to secure by Letters Patent of the United States, is:

A device of the class described, comprising a tie forming and securing member having a slightly curved upper portion and slightly inwardly turned and downwardly tapered edges, the lower portion of said member being of a semi-tubular shape adapted to receive one flap of a tie therein, and a 45 degrees circular disk-shaped piece pivotally fastened at the extreme outer edge at the lower end of said semi-tubular portion, said disk-shaped piece permitting of an outwardly swinging motion, and said disk-shaped piece having one of its rectangular sides shorter than the other side, whereby to allow ample space for the insertion of said tie flap.
